SHADE ROLLER WINDING DEVICE

Victor A. Hawkins, Brooklyn, N. Y.

Application January 22, 1946, Serial No. 622,759

1 Claim. (Cl. 81—3)

1

This invention relates to devices for the winding of the spring of a window shade roller when the same has lost its winding tension.

Shade rollers of the spring actuated type provided with a ratchet for arresting winding of the roller by the tension of the spring frequently lose their winding tension due to the slippage of the ratchet and from natural loss of tension strength of the spring due to wear. In such event it is the practice of housewives and others to remove the shade roller from its supporting brackets and grasp the squared end of the roller pindle between the thumb and forefinger and impart a turning movement thereto to rewind the spring. Such method of rewinding the spring is tedious and dangerous for it is difficult to obtain a firm grip on the roller pindle and after a tension is built up in the spring the fingers of the operator may slip and should the ratchet not catch, the operator's fingers may be injured. Therefore, the principal object of this invention is to provide a device which may be fitted into the square winding pindle of a shade roller for facilitating the easy and safe winding of the spring when the tension sufficient to actuate the roller has become spent.

Another feature of the invention resides in a winding key for window shade rollers in which the manipulating member thereof is offset with respect to roller pindle connection so as to provide leverage during a winding operation.

Other features of the invention are to provide a shade roller winding device which is simple and inexpensive of construction, easy to apply and remove from the winding pindle of a shade roller, and capable of being stored away in a small space when not in use.

Other novel features of the invention will become apparent as the following specification is read in conjunction with the accompanying drawing, in which,

Figure 1 is a perspective view of the winding device applied to the winding pindle of a conventional window shade roller.

Figure 2 is a front elevational view of the winding device per se.

Figure 3 is an edge elevational view.

Figure 4 is a horizontal sectional view on the line 4—4 of Figure 2.

Referring to the drawing by reference characters the numeral 10 designates my window shade spring winding device in its entirety which is preferably constructed of metal and includes a rigid disk-like body 11 having a relatively short arm 12 integral therewith and extending at right angle from one flat side of said body at a portion of the peripheral edge thereof. The flat body 11 constitutes a finger manipulating portion which may be grasped between the thumb and forefinger of the hand of a user. The arm 12 is provided with a rectangular shaped slot 13, the length of which is parallel to the adjacent flat face of the body 11. The slot 13 is of a size to

2

freely fit upon the flat pindle 14 of a conventional shade roller 15 on which a shade 16 is windable. This pindle 14 is connected to the spring winding shaft 17 of the roller 15 and which shaft is held against unwinding by the tension of the spring by a ratchet 18.

In practice, assume that the window shade roller 15 has lost its spring tension and is unable to impart a winding of the shade 16 upon the roller. The shade and roller are removed from their normal supporting brackets and the device 10 is applied to the pindle 14 by inserting the pindle through the slot 13. The operator now grasps the flat manipulating portion 11 between the thumb and forefinger of the hand and proceeds to turn the device about the axis of the shaft 17, the ratchet 18 acting to prevent any unwinding during any brief pause during the complete winding operation. When the roller actuating spring has been wound to the proper tension, the device 10 is withdrawn from its engagement with the pindle 14 and the roller and shade replaced upon its hanger brackets.

From the foregoing description it will be understood that I have provided a simple and inexpensive winding device which may be kept handy in a household for use in winding the spring of a conventional shade roller to restore lost tension therein, thus eliminating the danger of injury by direct winding with one's fingers, or by the use of pliers or other unappropriate make-shift devices.

While I have shown and described what I consider to be the preferred embodiment of my invention, I wish it to be understood that such changes in construction, material, and design as come within the scope of the appended claim may be resorted to if desired without departing from the spirit of the invention as set forth therein.

Having thus described the invention, what I claim as new and desire to secure by Letters Patent is:

A device for operating the spring-winding pindle of a shade roller to effect a winding of the spring in said roller, comprising a disk-shaped body, and a fixed lug on the body and extending outward from one face adjacent the periphery thereof, said lug having a rectangular opening therethrough with opposite parallel inner faces, to engage said pindle, the length of the opening being parallel to the body.

VICTOR A. HAWKINS.
